UNITED STATES PATENT OFFICE.

WENDELL P. THORÉ, OF BOSTON, MASSACHUSETTS, ASSIGNOR TO GENERAL ELECTRIC COMPANY, A CORPORATION OF NEW YORK.

DESIGN FOR A LAMP AND SUPPORT.

43,292.

Specification for Design.

Patented Nov. 26, 1912.

Application filed December 26, 1911. Serial No. 668,000. Term of patent 14 years.

To all whom it may concern:

Be it known that I, WENDELL P. THORÉ, a citizen of the United States, residing at Boston, in the county of Suffolk and State of Massachusetts, have invented a new, original, and ornamental Design for a Lamp and Support, of which the following is a specification.

The accompanying drawing is a view of my ornamental electric lamp support and lamp, in which the globe A, which incloses the source of light, is made of light transmitting material.

What I claim is,—

The ornamental design for a lamp and support as shown and described.

In witness whereof, I have hereunto set my hand this twenty second day of December, 1911.

WENDELL P. THORÉ.
